Primary Examiner — Richard Kearney*Assistant Examiner* — Anthony Vincent Rotolo(74) *Attorney, Agent, or Firm* — Sam Pierce(57) **CLAIM**

The ornamental design for the rechargeable RGB LED light as shown and described.

DESCRIPTION

FIG. 1 is a front perspective view of the rechargeable RGB LED light, showing my new design;

FIG. 2 is a rear perspective view of the rechargeable RGB LED light thereof;

FIG. 3 is a front view of the rechargeable RGB LED light thereof;

FIG. 4 is a rear view of the rechargeable RGB LED light thereof;

FIG. 5 is a left side view of the rechargeable RGB LED light thereof;

FIG. 6 is a right side view of the rechargeable RGB LED light thereof; and,

FIG. 7 is a top view of the rechargeable RGB LED light thereof.

The broken lines in the figures illustrate portions of the rechargeable RGB LED light that form no part of the claimed design.
